UNITED STATES PATENT OFFICE.

LESTER KIRSCHBRAUN, OF CHICAGO, ILLINOIS.

PROCESS FOR MAKING WATERPROOF FELTED COMPOSITIONS.

Application filed September 10, 1919. Serial No. 322,831.

To all whom it may concern:

Be it known that I, LESTER KIRSCHBRAUN, a citizen of the United States, residing in the city of Chicago, county of Cook, and State of Illinois, have invented certain new and useful Improvements in Processes for Making Waterproof Felted Compositions, of which the following is a specification.

This invention relates to improvements in process for making waterproof felted compositions and has among its salient objects, to provide a process in which the fibre is waterproofed simultaneously with the formation of the sheet on the paper machine; to provide a process in which the last mentioned object is accomplished without sticking up or gumming the machine or otherwise interfering with its operation due to the use of a normally adhesive bitumen or other similar waterproof pitch; to provide a process in which the waterproof felted composition is formed into a sheet with a fabric backing which fabric backing is fed continuously to the machine and in effect serves as a forming screen for the felted sheet; to provide a process which permits the formation of the sheet without the use of blankets or wire screens; to provide a process in which fibres of the felted sheet are not only mechanically interlocked with the latter during the formation of the felted sheet but are also adhesively bound thereto by the pitchy binder which is used as a saturant or waterproofing agent; to provide a novel product in which the felted sheet is interlocked with a fabric backing; and in general to provide a process of the character referred to.

In the drawings:

Fig. 1 is a somewhat diagrammatic side elevation of my improved apparatus.

Fig. 2 is an end elevation of the forming cylinder.

Referring to the drawings, 1 designates a vat provided with an inlet pipe 2 for the stock and provided with a false bottom 3. Above the false bottom 3 is mounted the stationary cylinder 4 comprised essentially of end plates 5 and 6 and a periphery 7 formed of idler rolls 8 which rotate on their axes in the stationary discs or plates 5 and 6. This cylinder 4 is detachably mounted in the vat so that it can be readily removed therefrom for cleaning or otherwise. At the upper side of the vat is mounted a pair of idler rolls

9 and 10 and at the lower end of vat a similar roll 11, for the purpose hereinabove described. At the rear of the vat is mounted a supporting frame 12 carrying a series of suction boxes 13 and table rolls 14. At the front end of the suction box is a dandy roll 15. At the rear end thereof are a pair of opposed pressure rolls 16 and similar rolls 17 and 17', the latter being a suction roll. At the rear of the roll 17 and 17' are still further pressure rolls 18 and then a series of drying rolls 19. The suction is applied to the suction boxes 13 and to the rolls 17' in a manner well known to those skilled in the art and need not therefore be described in detail. The particular arrangement of these rolls can of course be modified to meet conditions. At the front of the machine is a reel 20 and a series of loopers 21, the latter being used to facilitate splicing in a well known manner. To prevent the water from carrying the stock in the vat between the fabric backing and the rollers on the cylinder, I provide at either side of the latter, a pair of straps 22 and 23 which serve the double function of accomplishing the process just described and also gauging the width of the sheet being formed. It is also to be noted that the rolls 16 are drive rolls being driven in the usual manner from any suitable source of power (not shown) so as to carry the sheet over the machine. The water which passes through the meshes of the fabric backing and into the cylinder is drawn out through pipe 24 connected by branch 25 to suction pump (not shown). A leg 26 is provided to register the level of the water in the cylinder.

Describing the manner of carrying out the process and operating the machine, a roll of fabric backing such as burlap is mounted on a reel and fed over the loopers, thence over the rolls 11, 10 and 9 and around the idler rolls 8. The fabric then passes under the roll 15 and through the rolls 16, 17, 17', 18 and the drying rolls 19. After the fabric backing is threaded through the machine in the manner just described, the stock is allowed to run into the vat. This stock may consist of fibrous pulp such as rags, sulphate, sulphite, newspapers or the like with sawdust added if desired and is preferably intimately mixed with a waterproof pitchy binder of a non-adhesive character. This binder may consist of an emulsion of col-

- loidal clay, water and bitumen the emulsion being so formed that the bitumen is in the internal phase and the clay and water in the external phase. As the fabric backing 5 passes through the vat, it picks up the fibre which is formed into a sheet as it passes over the machine, the water removed by suction and drying rolls and the bitumen thereupon becoming again adhesive and uniting 10 with the fibre and with the fabric backing. Stock is fed over the machine in such a consistency as to permit the fibres to felt and interlace or interlock with each other and also with the fabric backing.
- 15 I claim as my invention:
1. A process of making felted fibrous compositions consisting in feeding an open mesh fabric backing over a paper forming machine forming thereon fibrous stock in an aqueous vehicle thereby causing the stock to 20 felt and interlock with the fabric backing, and simultaneously with said operation introducing a waterproof pitchy binder.
  2. A process of making felted fibrous compositions consisting in feeding an open mesh fabric backing over a paper forming machine forming thereon fibrous stock in an aqueous vehicle thereby causing the stock to 25 felt and interlock with the fabric backing, and simultaneously with said operation introducing a waterproof pitchy binder, said pitchy binder being in the form of a non-adhesive emulsion while in the aqueous vehicle and during the felting operation.
  3. A product of the character described, 30 consisting in a fabric backing sheet and a

felted waterproof fibrous body the fibres of which are interlocked with the meshes of the fabric sheet and a waterproof bituminous adhesive binder uniting the fibers to the fabric sheet. 40

4. A product of the character described, consisting of a fabric backing sheet upon which has been formed and to which is integrally united a felted fibrous body of 45 paper stock containing a waterproof pitchy binder.

5. A process of making a felted fibrous composition consisting in passing an open mesh fabric sheet through a vat containing 50 paper stock in an aqueous vehicle, causing the paper stock to felt on the fabric, removing the water and drying the sheet and impregnating the product with an adhesive waterproof binder introduced as a non-adhesive emulsion during said felting operation. 55

6. A reenforced fibrous composition sheet comprising an open mesh body portion and a fibrous composition adhering thereto and 60 comprising fibres coated with a bituminous material, said fibres being permanently felted.

7. A reenforced fibrous composition sheet comprising an open mesh body portion and 65 a fibrous composition adhering thereto and comprising fibres coated with a bituminous material, said fibres being permanently felted, said fibrous composition passing through the meshes of the reenforce.

LESTER KIRSCHBRAUN.
